Patented Sept. 18, 1962

193,632

LAMP

David Patience, Jr., Chicago, Ill., assignor to Rembrandt Lamp Corporation, Chicago, Ill., a corporation of Illinois

Filed Aug. 7, 1961, Ser. No. 66,365

Term of patent 7 years

(Cl. D48—20)

FIG. 1 is a side elevational view of a lamp showing my new design; and

FIG. 2 is a top plan view hereof.

The bottom of the shade is open and conventional.

I claim:

The ornamental design for a lamp, substantially as shown and described.
